CLAIM

The ornamental design for a drifting kart, as shown and described.

DESCRIPTION

FIG. 1 is a top, rear, and right side perspective view of a drifting kart showing my new design in accordance to a first embodiment;

FIG. 2 is a top, front, and left side perspective view thereof;

FIG. 3 is a front elevation view thereof;

FIG. 4 is a rear elevation view thereof;

FIG. 5 is a left side elevation view thereof;

FIG. 6 is a right side elevation view thereof; and

FIG. 7 is a top plan view thereof.

FIG. 8 is a top, rear, and right side perspective view of a drifting kart showing my new design in accordance to a second embodiment;

FIG. 9 is a top, front, and left side perspective view thereof;

FIG. 10 is a front elevation view thereof;

FIG. 11 is a rear elevation view thereof;

FIG. 12 is a left side elevation view thereof;

FIG. 13 is a right side elevation view thereof; and,

FIG. 14 is a top plan view thereof.

Broken lines are used to illustrate features of the drifting kart which form no part of the claimed design. Dash-dot lines indicate a boundary of claimed subject matter.
